(57) **CLAIM**

The ornamental design for an umbrella for delivery and dispersion of cryogenic liquids, as shown and described.

DESCRIPTION

FIG. 1 is a back perspective view of an umbrella for delivery and dispersion of cryogenic liquids showing my new design; FIG. 2 is a left side elevation view;

FIG. 3 is a right side elevation view;

FIG. 4 is a back elevation view;

FIG. 5 is a front elevation view;

FIG. 6 is a top plan view;

FIG. 7 is a bottom plan view; and,

FIG. 8 is a left side elevation view of the umbrella for delivery and dispersion of cryogenic liquids shown in use.

In FIG. 7, the broken lines depict unclaimed subject matter only and form no part of the claimed design. In FIG. 8, the broken lines shown in the drawings are for the purpose of illustrating environment that forms no part of the claimed design.
